UNITED STATES PATENT OFFICE.

GUSTAV R. SCHIMMEL, OF DETROIT, MICHIGAN.

DESIGN FOR A FLY-PAPER HOLDER.

SPECIFICATION forming part of Design No. 34,206, dated March 12, 1901.

Application filed February 11, 1901. Serial No. 46,945. Term of patent 7 years.

To all whom it may concern:

Be it known that I, GUSTAV R. SCHIMMEL, a citizen of the United States of America, residing at Detroit, in the county of Wayne and State of Michigan, have invented a certain new and original Design for Fly-Paper Holders, of which the following is a specification, reference being had therein to the accompanying drawings, forming part thereof, in

10 which—

Figure 1 is a front elevation of the holder. Fig. 2 is a vertical central section through the holder.

15 As shown in the drawings, the leading or material feature of my design consists of

the peculiar outline and configuration of the holder produced by the shape of the vessel A and the paper-holder B, forming an upward extension of the same.

Having thus fully described my invention, 20 what I claim as new, and desire to secure by Letters Patent, is—

The design for a fly-paper holder, substantially as herein shown and described.

25 In testimony whereof I affix my signature in presence of two witnesses.

GUSTAV R. SCHIMMEL.
